UNITED STATES PATENT OFFICE.

ELMER R. NEVEL, OF LOCK HAVEN, PENNSYLVANIA.

HOT-AIR-FURNACE ATTACHMENT.

Application filed March 6, 1928. Serial No. 259,498.

The present invention relates to improvements in hot air furnaces and has reference more particularly to an attachment to the circular radiating drum for increasing the radiating surface thereof.

One of the important objects of the present invention is to provide a hot air furnace attachment that can be readily and easily installed without necessitating any material alterations of the parts of the furnace with which the present invention is associated.

A still further object of the invention is to provide a hot air furnace attachment which is simple in construction, inexpensive, strong and durable and further well adapted to the purpose for which it is designed.

Other objects and advantages of the invention will become apparent during the course of the following description when taken in connection with the accompanying drawings.

In the accompanying drawings wherein like reference characters indicate corresponding parts throughout the several views:

Figure 1 is a horizontal sectional view through a hot air furnace showing a circular radiating drum in top plan and fragmentarily disclosing one form of the present invention.

Figure 2 is a side elevation of the circular radiating drum showing the manner in which the vertically disposed radiating fins are associated with the drum.

Figure 3 is an enlarged sectional view showing the adjusting means for urging the radiating units against the circular radiating drum.

Figure 4 is a fragmentary detail perspective view of the circular strap or band that forms a part of this form of the invention.

Figure 5 is a detail elevational view of a pair of the U-shaped radiating fins showing the manner in which the same are arranged in spaced relation with respect to each other.

Figure 6 is a view similar to Figure 1 showing the type of radiating fins that are used in conjunction with a horseshoe shaped radiator of a hot air furnace.

Figure 7 is a detail perspective view of one of the radiating fins.

Figure 8 is a sectional view showing two adjacent fins and the band that extends through the openings formed in the fins for cooperation with the laterally disposed lugs struck out from the fins, and

Figure 9 is a fragmentary detail perspective view of one end portion of the band.

In the drawings with reference more particularly to Figures 1 to 5 inclusive, the numeral 1 designates the circular radiating drum of a hot air furnace A. A plurality of substantially U-shaped brackets designated by the numeral 2 have the ends of the arms thereof secured to the outer peripheral face of the drum in any appropriate manner and these radially disposed brackets are arranged at spaced points as more clearly shown in Figures 1 and 2.

The upper and lower arms of each U-shaped bracket are formed with longitudinally extending registering slots 3 and 4.

Extending circumferentially around the radiating drum 1 and through the spaced brackets 2 for disposition adjacent the crown portions of the bracket is the sectional relatively wide ring 5. An inwardly directed flange 6 is formed on the lower edge of each section for rest upon the lower arms of the respective brackets and extending upwardly from the inwardly directed flange 6 of each section of the segmental ring 5 are the spaced lugs 7 and this feature is more clearly disclosed in Figure 4 of the drawings.

Forming a salient part of this invention are the U-shaped heat radiating fins designated by the numeral 8, the same being preferably formed of copper, although any other suitable material may be employed.

These U-shaped fins or units 8 are disposed radially around the drum 1 and the open ends of these fins are adapted for disposition against the drum while the crown portions of the U-shaped fins engage with the inner face of the respective sections of the segmental ring 5. The lower edge of the crown portion of each fin is adapted to rest on the inwardly directed flange 6 and as is shown very clearly in Figure 5, the lugs 7 tend to properly space the adjacent fins with respect to each other so that vertical air passages will be provided between the fins as well as between the arms of each fin.

Furthermore, the longitudinal slots 3 and 4 formed in the upper and lower arms of each bracket will permit the free circulation of the air upwardly therethrough as indicated by the arrows in Figure 3.

An adjusting screw 9 is threaded through the central portion of the crown or base of each U-shaped bracket 2 for engagement with the outer face of the adjacent section of the

segmental ring 5 whereby to urge the sections of the ring inwardly and to force the U-shaped heat radiating units 8 inwardly against the drum 1 so that the fins will be rigidly supported in a radial manner around the drum.

With reference now to Figures 6 to 9 inclusive wherein there is shown another form of the invention for use in conjunction with 10 hot air furnaces provided with horse shoe shaped radiators, the numeral 10 designates the horse shoe shaped radiating drum.

A relatively narrow flat band 11 extends around the outer peripheral face of this 15 drum 10 in spaced relation with respect thereto and the free ends of the band are disposed inwardly as at 12, and are secured to the respective ends of the horse shoe shaped drum by any appropriate fastening means 20 shown at 13 in Figure 6.

A series of vertically disposed copper plates of rectangular shape and designated by the numeral 14 constitutes the heat radiating fins and each plate is formed with a slot 25 or opening 15 adjacent the outer edge thereof. A lug 16 extends laterally from the inner edge of this slot 15 and each lug is slightly curved so as to positively engage with the inner peripheral face of the horseshoe band 30 11 that extends through the registering slots 15 formed in the plate 14 and furthermore the lugs 16 provide a means for maintaining the plates in spaced relation with respect to each other and these plates will have their 35 inner edges disposed against the outer peripheral face of the horse shoe shaped drum 10 as clearly disclosed in Figures 6 and 8 of the drawings.

It will thus be seen from the foregoing description that I have provided an attachment 40 for a hot air furnace that will increase the radiating surface of the radiator that is arranged above the fire pot of the furnace, and due to its simplicity, the attachment can be 45 readily and easily installed without necessitating any material alterations of the parts of the furnace with which said invention is associated.

While I have shown the preferred embodiment of my invention, it is to be understood 50 that minor changes in the size, shape and arrangement of parts may be resorted to without departing from the spirit of the invention and the scope of the appended claims.

Having thus described the invention, what 55 I claim as new is:—

1. The combination with the radiating drum of a hot air furnace, of a plurality of brackets carried by the drum and extending 60 radially therefrom, a sectional ring encircling the drum and confined within the brackets adjacent the outer ends thereof, a series of radiating fins arranged radially 65 with respect to the drum, the inner edges of the fins engaging the drum, and means for

urging the ring inwardly against the outer edges of the fins to maintain the latter rigidly with respect to the drum.

2. The combination with the radiating drum of a hot air furnace, of a plurality of 70 brackets carried by the drum and extending radially therefrom, a sectional ring encircling the drum and confined within the brackets adjacent the outer ends thereof, a series of radiating fins arranged radially 75 with respect to the drum, the inner edges of the fins engaging the drum, means for urging the ring inwardly against the outer edges of the fins to maintain the latter rigidly with respect to the drum, said last mentioned means comprising an adjusting screw carried by each bracket and engaging the ring.

3. The combination with the radiating drum of a hot air furnace, of a plurality of 80 brackets carried by the drum and extending radially therefrom, a sectional ring encircling the drum and confined within the brackets adjacent the outer ends thereof, a series of radiating fins arranged radially 85 with respect to the drum, the inner edges of the fins engaging the drum, means for urging the ring inwardly against the outer edges of the fins to maintain the latter rigidly with respect to the drum, and means on the lower edge of the ring for supporting 90 the fins in spaced relation with respect to each other.

4. The combination with the radiating drum of a hot air furnace; of a plurality 100 of U-shaped brackets secured at their inner ends to the drum and extending radially therefrom, said brackets being arranged at spaced intervals, a sectional ring encircling the drum and being disposed within the U-shaped brackets adjacent the closed outer 105 end portion thereof, an inwardly directed flange formed on the lower edge of each section of the sectional ring, upwardly extending lugs formed on the flanges, and a plurality of vertically radiating units arranged 110 radially with respect to the drums, the outer ends of the units engaging the inner face of the sectional ring and adapted to rest on said flanges, said lugs cooperating with the units to space the same with respect to each other, and means carried by the brackets 115 for cooperation with the sectional ring to force the radiating units inwardly against the drum.

5. The combination with the radiating drum of a hot air furnace; of a plurality of 120 U-shaped brackets secured at their inner ends to the drum and extending radially therefrom, said brackets being arranged at spaced intervals, a sectional ring encircling 125 the drum and being disposed within the U-shaped bracket adjacent the closed outer end portion thereof, an inwardly directed flange formed on the lower edge of each section of the sectional ring, upwardly extending lugs 130

formed on the flanges, and a plurality of vertically radiating units arranged radially with respect to the drums, the outer ends of the units engaging the inner face of the sectional ring and adapted to rest on said flanges, said lugs cooperating with the units to space the same with respect to each other, means carried by the brackets for cooperation with the sectional ring to force the radiating units inwardly against the drum, said last mentioned means comprising an adjusting screw threaded through the closed outer end of each bracket and engaging the sectional ring.

6. The combination with the radiating drum of a hot air furnace, of a series of vertical radiating plates arranged greatly with respect to the drum, each plate being formed with a slot in the outer end portion thereof, a lug extending laterally from each plate for abutting engagement with the adjacent plate to maintain the plate in spaced relation with respect to each other, supporting means for the plates extending through the registering slots, said supporting means comprising a band, the lugs being arranged adjacent the inner sides of the slots, said band engaging said lugs to maintain the inner edges of the plates against the drum.

7. The combination with the radiating drum of a hot air furnace, of a series of vertical radiating plates arranged greatly with respect to the drum, each plate being formed with a slot in the outer end portion thereof, a lug extending laterally from each plate for abutting engagement with the adjacent plate to maintain the plate in spaced relation with respect to each other, supporting means for the plates extending through the registering slots.

7. The combination with the radiating drum of a hot air furnace, of a series of vertical radiating plates arranged greatly with respect to the drum, each plate being formed with a slot in the outer end portion thereof, a lug extending laterally from each plate for abutting engagement with the adjacent plate to maintain the plate in spaced relation with respect to each other, supporting means for the plates extending through the registering slots, said supporting means comprising a band, the lugs being arranged adjacent the inner sides of the slots, said band engaging said lugs to maintain the inner edges of the plates against the drum.

In testimony whereof I affix my signature.

ELMER R. NEVEL.
